UNITED STATES PATENT OFFICE.

JOHN H. HUNT AND HUGH WALLACE, OF DAYTON, OHIO, ASSIGNORS TO THE DAYTON ENGINEERING LABORATORIES COMPANY, OF DAYTON, OHIO, A CORPORATION OF OHIO.

FUEL BURNER.

Application filed May 10, 1922. Serial No. 559,955.

To all whom it may concern:

Be it known that we, JOHN H. HUNT and HUGH WALLACE, citizens of the United States of America, residing at Dayton, county of Montgomery, State of Ohio, have invented certain new and useful Improvements in Fuel Burners, of which the following is a full, clear, and exact description.

This invention relates to liquid fuel burners and more particularly the type constructed and arranged to operate by means of suction produced by an internal-combustion engine and for the purpose of heating the fuel mixture supplied to the engine by the carburetor so as to assist in vaporizing the fuel so that it may be readily ignited by the electric spark.

The type of apparatus to which the present invention is applied includes a burner to which a liquid fuel is supplied from the float bowl to the engine carburetor and the products of combustion of the burner pass into a chamber generally known as an adapter which provides a flame chamber surrounding a portion of the engine intake, this adapter being a support for the burner and forming a connection between the carburetor and the engine intake. In the co-pending application of John H. Hunt, Serial No. 479,764, filed June 23, 1921, means are provided for regulating the effect produced by engine suction upon the burner so that the burner will be substantially constant in operation over a wide variation of engine suction. In this application a valve was provided to control a passage between the burner combustion chamber and the engine intake and automatic means was provided for controlling this valve in such a manner that as the engine suction increases, this valve tended to close said passage thereby tending to maintain suction in the burner combustion chamber uniform. Therefore it is apparent that the amount of liquid fuel and air admitted to the burner would remain substantially constant. In the said invention it is obvious that the automatic valve would be subjected to the action of the products of combustion of the

burner and extra precautions needed to be taken in order that the valve port would not coke up, and the valve itself needed to be constructed of special materials that would not deteriorate rapidly under the action of heat.

It is an object of the present invention to control the burner by means of a valve which regulates the burner fuel before the latter is ignited so that the valve will not be undesirably heated. In carrying out this object, it is a further object to provide a single port through which all of the air and liquid fuel to be consumed by the burner must pass and to control this port by a regulating valve so as to limit the amount of total fuel mixture supplied to the burner although there may be a wide variation of engine suction.

It is a further object of the invention to separate out from the total fuel mixture entering this port, an extra rich mixture which is readily ignitable by an electric spark when the burner is cold, so that the burner may be easily set into operation when cold.

A further object is to provide a manual control for said burner whereby to vary the rate of combustion and to render the burner inoperative.

Other and further objects of the present invention will be apparent from the following description, reference being had to the accompanying drawings, wherein a preferred embodiment of the present invention is clearly shown.

In the drawings:

Fig. 1 is a fragmentary side elevation of an automobile engine showing attached thereto a carburetor and a liquid fuel burner embodying the present invention. There is also shown a hand control of the burner which is operated from the dash of an automobile, the dash being shown in section;

Fig. 2 is a plan view of the liquid fuel burner shown in Fig. 1, this burner being shown on an enlarged scale and attached to a burner adapted which forms a connection between the engine carburetor and the

engine intake which is shown in section, the section being substantially on the line 2—2 of Fig. 1;

Fig. 3 is a sectional view taken on the line 3—3 of Fig. 2;

Fig. 4 is a sectional view taken on the line 4—4 of Fig. 2; and

Fig. 5 is a sectional view taken on the line 5—5 of Fig. 2.

10 In the drawings, 20 designates an internal-combustion engine having an intake manifold 21 to which is bolted a burner adapter 22 and a carburetor 23 by means of the bolts 24. Carburetor 23 may be of any type of carburetor having fuels adapted for automobile use and the type chosen for illustration is known as the Marvel, a well known make. The adapter 22 includes a flame chamber 25 which surrounds an insert 26 which provides a passage leading from the carburetor 23 into the engine intake 21. The products of combustion of the burner to be described, may pass from the flame chamber 25 into the engine intake 21 through the holes 27 provided in the wall of the insert 26. These holes 27 are located as shown nearest the carburetor 23 so that, the adapter being mounted with the insert 26 in a vertical position, the 25 products of combustion will travel around the outside of the insert 26 and pass through the holes 27. In this manner the heating effects of these products can be utilized more efficiently.

30 The adapter 22 is provided with a flange 28 to which is secured by means of bolts 29, a burner casting or frame 30 which is provided with a jet chamber 31 where the fuel from the jet is ignited and begins to burn slowly, and with a combustion chamber 32 where the complete combustion of the fuel from the jet takes place. To the burner frame 30 is attached, by means of screws 33, a fuel separator 34 to which in turn is attached, by means of screws 35, a valve member 36. Valve 36 is provided with a valve cylinder 37 which slidably supports a piston or plunger 38 carrying a needle valve 39 which cooperates with a seat 40 for controlling a passage 41 leading into a passage 42. The valve 39 is yieldingly maintained in the position shown in Fig. 4 by means of a spring 43 held at its lower end within a recess 44 and having its upper end pressing against the plunger 38. The plunger 38 is in turn pressed against a disc 45 which is held in position by means of a valve frame cap 46 and attached to the valve frame 36 by means of screws 47. The cap 46 includes a chamber 48 for receiving the upwardly extending end 49 of the valve 39. This portion 49 is screw-threaded to receive nuts 50 which are adjusted to limit the downward or closing movement of the valve 39. The communication between the passages 41 and 42 is con-

trolled by means of valve 51 which is operated by means of a Bowden wire 52, which is operated by rod 53 from the dash 54 of an automobile. By pulling out on the rod 53 against the action of a spring 55, the valve 51 will be moved to open position as shown in Fig. 4, releasing the button 53 to cause the wire 52 and valve 51 to be moved to the left under the action of the spring 55.

The valve frame 36 supports a mixing chamber 60 communicating with external atmosphere through passages 61 and communicating with the cylinder 37 through a restricted passage 62 which surrounds the inner end of fuel nozzle 63 which is screw-threaded into the wall of the frame 36 surrounding the mixing chamber 60. Therefore it is seen that as the air is sucked into the cylinder through passages 61 and 62, a venturi effect will be produced upon the nozzle 63, causing fuel to be sucked into said nozzle through a pipe 64 connected therewith which communicates with the fuel in the carburetor float bowl 65 through a metering hole 66 which is preferably 14 thousandths of an inch in diameter. This pipe 64 is preferably about 1/8 of an inch in diameter and is provided with a small air metering hole 67 located above the level of the fuel in the bowl 65. Due to the suction of the engine a small quantity of air will be caused to enter at 67 and to be drawn up with the liquid fuel through the pipe 64 into the nozzle 63. As explained before additional air will be sucked through the passages 61 into the suction chamber 60. It is intended that all the air which is necessary for fuel atomizing and for fuel combustion shall pass with the liquid fuel through the passages 41 and 42 and through a passage 70 provided in the separator 34 into the separating chamber 71. The heavy fuel particles will drop by force of gravity to the bottom of this chamber 71 and will flow down an inclined portion 72, see Fig. 3, and through a fuel metering hole 73 which is preferably about 3/64 of an inch in diameter. The level of fuel in the chamber 71 will not be such as to cover entirely the hole 73 during the normal operation of the burner. But some air will enter with the liquid fuel through the passage 73 into the burner nozzle or jet member 74, and this relatively rich mixture of air and fuel will pass out through the small spray orifice 75 and this fine spray will be drawn without very great velocity toward the burner spark plug 76 which will ignite the jet by means of an electric spark passing across the points 77 and 78. The lighter fuel particles will pass with a greater part of the air which has entered into the separating chamber 71 through holes 80 provided in a plug 81 having a central bore 82 which is in communication with an air passage 83 provided in the burner frame 30 and which directs air 130

against a baffle 84 so that it will be contracted down into contact with the burning fuel jet so as to provide the air for complete combustion of the slowly burning fuel particles. The electric spark is preferably provided by means of a battery and ignition coil connected by a suitable switch. The high tension winding of the coil is connected in the usual manner with the burner spark plug, the other end of the secondary being grounded upon the engine or directly upon the burner frame if desired. If the burner flame does not ignite readily, a quantity of fuel will collect in a puddle cavity 90 arranged at the bottom of the burner jet chamber 31 and air may be drawn by engine suction through passages 91 and 92 and bubbler orifice 93 up through the puddle of fuel in cavity 90. The drawing of a small quantity of air through this puddle will cause the fuel to be sprayed upwardly and between the spark plug to assist in lighting the fuel jet.

The burner 30 is provided with a mica window 95 for inspecting the character of the burner flame.

It is apparent from the foregoing that the control of burner suction has been effected in a relatively simple manner and that the automatic valve which controls the burner is located so as to be readily accessible and that it is not affected by the heat of the burner. The manual control of the burner is effected in a simple manner since but one manually controlled valve is necessary to control both the air and liquid fuel consumed by the burner. In structures where combustion air is admitted to the fuel through a passage separate from the passage for the rich fuel mixture for the burner jet, the control of the burner in this manner would require separate valves for combustion air and for rich fuel mixture. But in the present invention air for combustion purposes and the rich fuel mixture are brought together and are caused to pass through one member which is automatically controlled, and then this matter is separated again into the relatively rich and relatively lean portions by virtue of the force of gravity so that the rich fuel mixture for the slow burning jet may be provided to the burner and later air for complete combustion of the burning jet may be supplied to the burner at a point between the burner jet nozzle and the engine intake.

When the burner is cold, three fuel mixtures are provided, the richest being provided by the puddle of fuel in cavity 90 and air bubbling up through this puddle through orifice 93. The next richest mixture comes out through the jets 75 and the leanest mixture which is nearly all air when the burner is cold comes in through passage 83. The puddle mixture is ignited first, it being pre-

sumed that the small particles of fuel bubbled up come in contact with the electric spark. These small particles assist in igniting the spray from the jets 75 and this flaming spray burns up with the leanest mixture 70 coming in through passage 83. As the burner warms up, the fuel will vaporize before reaching the jets 75 and therefore the puddle in cavity 90 will dry up. When the burner is fully warmed up little, if any, 75 separation of the fuel mixture will take place, and the fuel mixture following the path of least resistance will pass into the combustion chamber 32 and will be kept ignited by the heated walls of the chamber with assistance from the spark plug, if necessary.

While the form of mechanism herein shown and described constitutes a preferred form of embodiment of the invention, it is to be understood that other forms might be 85 adopted, all coming within the scope of the claims which follow.

What we claim is as follows:

1. In a device for heating an engine intake, the combination with an internal-combustion engine; of an electrically ignited liquid fuel burner communicating with the intake of said engine; means operated by engine suction for supplying the burner with a total fuel air mixture; and means for separating out of said total fuel mixture, when the burner is relatively cool, a relatively rich easily ignitable mixture.

2. In a device for heating an engine intake, the combination with an internal-combustion engine; of an electrically ignited liquid fuel burner communicating with the intake of said engine; means operated by engine suction for supplying the burner with a total fuel air mixture; and automatic 105 means for limiting the amount of total mixture over a relatively wide range of engine suction.

3. In a device for heating an engine intake, the combination with an internal-combustion engine; of an electrically ignited liquid fuel burner communicating with the intake of said engine; means operated by engine suction for supplying the burner with a total fuel air mixture; and automatic 110 means for limiting the amount of total mixture over a relatively wide range of engine suction; and means for separating out of said total fuel mixture, when the burner is relatively cool, a relatively rich easily ignitable mixture.

4. In a device for heating an engine intake, the combination with an internal-combustion engine; of an electrically ignited liquid fuel burner communicating with the intake of said engine; means operated by engine suction for supplying the burner with a total fuel air mixture; and automatic means for limiting the amount of total mixture over a relatively wide range of engine suction; 125

and means for rendering the burner inoperative.

5. In a device for heating an engine intake, the combination with an internal-combustion engine; of an electrically ignited liquid fuel burner communicating with the intake of said engine; means operated by engine suction for supplying the burner with a total fuel air mixture; and automatic 10 means for limiting the amount of total mixture over a relatively wide range of engine suction; and means for separating out of said total fuel mixture, when the burner is relatively cool, a relatively rich easily ignitable mixture; and means for rendering the burner inoperative.
- 15

6. In a device for heating an engine intake, the combination with an internal-combustion engine; of a liquid fuel burner communicating with the intake of the engine; a 20 duct through which a total fuel-air mixture is supplied to said burner; and means for automatically regulating the amount of fuel mixture supplied through said duct.

In testimony whereof we hereto affix our ~~26~~ signatures.

JOHN H. HUNT.
HUGH WALLACE.
